GLOBE HOLDER FOR ELECTRIC LIGHTING FIXTURES

Filed Oct. 11, 1926

Ernest Cawell White

INVENTOR

UNITED STATES PATENT OFFICE.

ERNEST CANTELO WHITE, OF NEW YORK, N. Y., ASSIGNOR OF ONE-HALF TO R. FENTON FISHER, OF PHILADELPHIA, PENNSYLVANIA.

GLOBE HOLDER FOR ELECTRIC-LIGHTING FIXTURES.

Application filed October 11, 1926. Serial No. 140,744.

My invention relates to the construction of globe holders for all types of electric lighting fixtures using globes having an opening through which the lamp must be inserted before the holder is attached. It also relates to the construction of holders for globes having an upturned lip at the point where the holder is attached. The disadvantages of supporting such globes by the old method of screws bearing against the under-side of the lip are well known in the trade and many improved means have been devised and marketed for overcoming these disadvantages. My invention is an improvement upon all of these in various particulars which are herein described.

One of the objects of my present invention is to provide a globe holder formed entirely of definitely formed non-resilient parts. Another object is to do away with all screws, latches, springs, triggers, pins, lugs and other small parts. Another object is to depend solely upon gravity for the proper support of the globe in the holder without any tightening means to limit the free expansion of a glass globe under changes of temperature. Still another object is to provide a holder which will effect a complete closure of the globe opening so that neither dust nor insects will find access to the interior of the globe. Another object is to provide broad surface support for the inside surface of hanging globes adjacent to the lip at which point these surfaces are commonly conoidal. A still further object is to provide a holder which can be constructed of insulating material and so combined with the lamp socket and supporting means as to provide a minimum number of parts.

In the accompanying drawings, Fig. 1 is a side view of the socket cover; Fig. 2 is a bottom view of the socket cover; Fig. 3 is a side view of the globe supporting member; Fig. 4 is a bottom view of the globe supporting member; Fig. 5 is a half side elevation and half cross section on line 5—5 Fig. 6 of the globe closing member; Fig. 6 is a bottom view of the globe closing member; Fig. 7 is a vertical longitudinal section of the several devices in assembled relation, and showing the lip portion of a globe operatively connected therewith, the supporting cable, lamp socket member and a lamp being shown in side elevation; Figs. 8 and 9 are side views

of the assembled holder and a lamp and a cross sectional view of a globe into which it is being inserted.

In carrying out my invention according to the illustrated embodiment thereof I construct the socket cover of moulded insulating material with an internal thread 1 and an external cylindrical portion 2. The internal arrangement of the socket cover is the same as described in my co-pending application Serial No. 139,991, filed October 7th, 1926. 65 I also preferably construct the globe supporting member of moulded insulating material with a neck 3 having external threads 4 adapted to screw into the socket cover, a center opening 5 to slip over the screw-shell of the 70 socket and two arms 6, 6 formed like the remaining portions of a stepped conoid with two sides cut away. The globe closing member is formed of any light weight moulded material having the desired finish with an 75 internal cylindrical portion 7 of the correct diameter to give an easy sliding fit over the cylindrical portion of the socket cover and with a rim 8 deep enough to accommodate the lip of a globe and of the right diameter 80 to give a loose engagement therewith.

The globe supporting member is assembled with the socket cover, a lamp socket interior and cable in substantially the same manner as described in my copending application 85 Serial No. 139991 already referred to, and in which the lamp socket has a lateral enlargement beneath which the upper end of the globe supporting member abuts to support and retain said socket member within the 90 socket cover. The end 9 of the socket cover is then seated against the shoulder 10 of the globe supporting member and the socket interior is supported by the end of the neck of the globe supporting member and is definitely positioned with respect thereto. A lamp is then screwed into the socket and the assembled parts as shown in Figs. 8 and 9 are ready to receive the globe to be used. 95

It is evident that the form of the globe 100 supporting member is of the greatest importance. The inside surface of a globe surrounding the lamp opening may be substantially horizontal but where it is formed into an upturned lip it becomes conoidal. This is the 105 point at which the globe should rest securely on broad surfaces of corresponding contours in order to provide against undue strains. I,

therefore, provide substantial horizontal bearings 11 at the ends of the arms 6 and shoulders 12 which are shaped like portions of a conoid having the same axis as the neck of 5 the member. The shoulders 12 are diametrically spaced so as to loosely fit the lower inside of the lip of the globe 15 to be used. When the globe 15 is resting on the globe supporting member as illustrated in Fig. 7 its 10 security must to a large extent depend upon the height of the shoulders 12 above the bearings 11. To provide for this I make this height greater than the radius of the corner 15 formed by the inside surfaces of the globe and the upturned lip thereof. For globes having no lip at all at the lamp opening, the radius of this corner is comparatively small and the shoulder 12 can safely be made lower than illustrated.

20 In order to make the arms 6 wide enough to provide a stable support these arms are formed with a horizontal portion 13 and a second conoidal or conical shoulder of smaller diameter 14. It should be observed that the 25 thickness of the arms up to the shoulder 14 is approximately uniform which provides certain spaces between the lower side of the arms and the neck of the lamp which are essential in the use of the holder.

30 In putting a globe on the holder the lamp 17 is first inserted into the globe and then moved sideways so that one side of the lip of the globe is moved up into the space between the neck of the lamp and the under-side of 35 one of the arms. This permits the other arm to be inserted into the globe by tilting it as shown in Fig. 8. The globe is then moved up on the arm first inserted until the lip of the globe reaches the corner between the surface 13 and the shoulder 14 as illustrated in Fig. 40 9. This permits the other arm of the globe supporting member to be inserted into the globe which may then be dropped into place 45 on the bearings 11 as illustrated in Fig. 7. The globe closing member, which may be raised 50 up out of the way and is omitted from Figs. 8 and 9, is then dropped down over the socket cover until the rim 8 rests upon the shoulder of the globe giving the complete assembly as 55 illustrated in Fig. 7. As the globe closing member is centered with the other parts by contact between the surfaces 7 and 2, the rim 8 engages the outside of the lip of the globe so that if the globe is raised the globe closing 60 member will be carried in fixed relation therewith. The length of the cylindrical portion of the socket cover is such that the globe must be raised up quite a ways with respect to the 65 socket cover, socket and lamp before the globe closing member can be tilted with respect to the socket cover. As the globe closing member slides freely up and down the socket cover in any position the weight of the parts results in their remaining centered on substantially 70 the same axis so that while the globe may be

raised up with respect to the holder the globe closing member will be raised with it and when the globe is lowered again the globe closing member will follow it down and insure the seating of the globe on the bearings 11. As 70 it is practically impossible to tilt the globe closing member with respect to the socket cover it is, therefore, equally difficult to rock the globe with respect to the socket cover because the globe cannot be moved sideways on 75 account of the shoulders 12 and is not easy to move vertically one side at a time because of the binding effect caused by such attempted displacement between the globe closing member and the socket cover. The globe may, however, be very easily and quickly removed by first sliding the globe closing member straight up with respect to the socket cover and then raising the globe above the shoulders 12 and tilting it so that first one arm, 80 then the other arm, and then the lamp may be withdrawn from the globe in the order named.

It will be evident that with this improved construction it is practical to have a close insect-proof fit between the rim 8 and the top 90 of the globe and between the surface 7 of the globe closing member and the surface 2 of the socket cover. There are no screws or small parts or small openings of any kind needed 95 for any purpose. The globe may be mounted on the holder or dismounted very rapidly and without tools of any kind. The rim 8 allows plenty of space for expansion of the lip of the globe when heated by the lamp. Yet when completely assembled it is impossible to dislodge the globe from the holder by swinging or shaking the supporting cable.

In constructing my improved holder the following essential relation of parts must be 105 carefully observed. The distance from the outside end of one of the bearings 11 to the outside of the opposite shoulder 12 must be greater than the diameter of the opening in the globe. The distance from the end of one of the bearings 11 to the outside of the opposite shoulder 14 must be less than the diameter 110 of the opening in the globe with an amount of clearance determined partly by the width of the arms. The distance from the end of one of the bearings 11 to the opposite side 115 of the neck of the lamp when assembled must also be less than the diameter of the opening in the globe. The outside diameter of the arms 6 may commonly be made the same as the outside diameter of the upwardly and outwardly turned lips of ordinary commercial 120 globes used at the present time.

The globe supporting member may if desired be constructed with three or more arms instead of two arms in which case the arms are 125 made much narrower but all of the essential relations of parts above described remain the same with slightly increased clearances and the function of the principal shoulders and corresponding bearings remain the same. In 130

fact my improved holder may be constructed in many different ways and of many different materials and what I claim as new is:

1. A combined socket-cover and globe holder for incandescent electric lamps, comprising a socket-cover having an internally threaded opening at its lower end, a socket member housed in said socket cover, said socket member having a laterally projecting portion, an integral retaining sleeve and globe support having an externally threaded upper end to screw into said internally threaded opening of said socket cover to abut said laterally projecting portion of said socket member in supporting and retaining relation thereto and having external arms laterally extending from its lower end with the extremities thereof disposed in substantially horizontal plane to provide globe supporting seats, and an annular keeper member vertically slidable on said socket cover and having a depending circumferential skirt to embrace the suspension lip of a globe engaged on said seats.
2. A combined socket-cover and globe holder, comprising a lamp socket member having radial lugs and a depending screw shell, a socket cover having an internally threaded opening at its lower end for the insertion of said socket member and recesses above said opening to receive said socket member lugs, an integral retaining sleeve and globe support having an externally threaded upper end to screw into said internally threaded opening

of said socket cover to surround said screw-shell and bear upwardly against said socket member lugs and having external arms laterally extending from its lower end with the extremities thereof disposed in substantially horizontal plane to provide globe-supporting seats, and an annular keeper member vertically slidable on said socket cover and having a depending circumferential skirt to embrace the suspension lip of a globe engaged on said seats.

3. A combined socket-cover and globe holder for incandescent electric lamps, comprising a socket-cover, a socket member housed within said socket-cover, said socket member having a laterally projecting portion, an integral retaining sleeve and globe support having its upper end detachably connected to and within said socket-cover and around said socket member and disposed to abut said laterally projecting portion of said socket member in supporting and retaining relation thereto, said integral retaining sleeve and globe support having external arms laterally extending from its lower end with the extremities thereof disposed in substantially horizontal plane to provide globe supporting seats, and an annular keeper member vertically slidable on said socket-cover and having a depending circumferential skirt to embrace the suspension lip of a globe engaged on said seats.

Signed at New York, N. Y., on this 9th day of October, 1926.

ERNEST CANTELO WHITE.
